UNITED STATES PATENT OFFICE.

JOHN E. MULLEN, OF SAN FRANCISCO, CALIFORNIA, ASSIGNOR OF ONE-HALF TO H. L. JUDELL & COMPANY, OF SAN FRANCISCO, CALIFORNIA.

SHOW CASE.

Application filed February 11, 1926. Serial No. 87,582.

My invention relates to improvements in show-cases and the like for the display and sale of merchandise wherein a top member is movable upwardly and rearwardly to give access to the case from the front thereof whereby the purchaser may select the goods desired.

The present invention is an improvement upon the device disclosed in my co-pending application Serial Number 53,836, filed Sept. 1, 1925, and consists of an improved construction and arrangement of elements adapted to obtain a more effective closure of the case and to obtain a more simple and efficient display case.

The primary object of the invention is to provide an improved show case wherein the top member is arranged to efficiently close the top of the case and to be efficiently locked against unauthorized opening.

Another object is to provide an improved device of simplified construction which will be highly efficient in operation.

A further object is to provide an improved construction in which the movable top member is efficiently guided along a prescribed path and normally held against movement other than the normal opening and closing movement thereof.

A still further object is to provide an improved construction which may be more economically manufactured and which will afford increased strength and durability.

I accomplish these and other objects by means of the improved device disclosed in the drawings forming a part of the present specification wherein like characters of reference are used to designate similar parts throughout said specification and drawings and in which,

Fig. 1 is a transverse section of my improved show case with the top member in closed position.

Fig. 2 is a transverse section with the top member in fully opened position.

Fig. 3 is a front elevation of the case, partly broken away to disclose the construction.

Fig. 4 is a rear elevation, parts being broken away to show the interior construction of the case.

Fig. 5 is a broken sectional detail showing the manner in which the top member engages the guiding cam.

Referring to the drawings my invention will be seen to consist of a case provided with end members 1 the upper edges of which are inclined downwardly toward the front of the cabinet. Beads 2 are secured upon the inner sides of the end members 1 parallel to the top edges thereof and in spaced relation thereto. The beads 2 form acute angles with the front member 3 of the case.

The back of the case consists of a fixed portion 4 extending across the lower portion of the back and a portion 6 pivotally mounted at its lower edge upon the fixed portion 4 by means of suitable hinges 7. Doors 8 and 9 are mounted in the back portions 4 and 6 respectively to give access to the case through the back thereof as hereinafter more fully explained. A top member 11 is pivotally connected at its rearward edge to the top of the movable back portion 6. The top member extends entirely across the top of the case and normally rests upon the beads 2 flush with the upper edges of the end members 1. The forward edge of the top member is beveled as at 12 to fit into the acute angle between the beads 2 and the front member 3 of the case, said beveled edge operating as a wedge pressing against the front members 3 and forcing the cover firmly down upon the beads 2 to obtain a tight and substantially dust proof fit. The beveled edge fitting against the front member 3 also serves to efficiently lock the top member against pivotal movement when in closed position as hereinafter more fully explained.

Cams 13 are mounted upon the inner sides of the end members 1 of the case adjacent the ends of the beads 2, said cams being provided with inwardly extending flanges 14 adapted to be slidably engaged by the top member 11. The ends of the cams adjacent the beads are arranged with the flange portions slightly spaced from the adjacent ends of the beads and substantially aligned therewith.

Retaining members 16 are secured upon the under sides of the top members 11 and arranged to engage the beads 2 and the flanges 14, said members 16 being arranged to engage the under sides of said beads and flanges to prevent pivotal movement of the top member 11 independently of its movement with the back portions 6 as herein-after described.

The top member consists of a frame provided with a transparent pane 11' and the front member 3 is preferably provided with a transparent pane 3' whereby the contents 5 of the case may be effectively displayed.

Shelves 17 are preferably provided within the case to support merchandise such as boxes of cigars or the like as indicated in dotted lines at 18.

10 In operation the case is closed by moving the back portion 6 and the top member 11 to closed position as shown in Fig. 1 of the drawings. When it is desired to open the case to permit a purchaser to select goods 15 therefrom, the back portion 6 is swung rearwardly upon its hinges 7. The rearward movement of the back portion 6 causes the top member 11 to be slid upwardly and rearwardly along the beads 2 and onto the 20 cams or guides 13. As the top member is moved rearwardly it is supported upon the cams 13 and as the rearward end is lowered with the back portion 6 the forward edge will be elevated a corresponding amount 25 until the top member is tipped rearwardly to a fully opened position as shown in Fig. 2 of the drawings. The members 16 engaging the under sides of the cams 13 hold the top 11 in engagement with said cams. As 30 the members 16 approach the rearward end of the cams 13 said members engage a suitable stop 19 limiting the movement of said members and thereby limiting the movement of the top 11 and back portion 6. The members 35 16 normally limit the movement of the top member 11 to its normal movement by and with the back portion 6 as above described, said members being arranged to engage the beads 2 and the flanges 14 to prevent independent pivotal movement of the 40 top member 11. Should it be desired to swing the top member 11 entirely away from the case for cleaning or for other purpose, the members 16 are moved opposite the 45 spaces 21 provided between the adjacent ends of the beads 2 and cams 13. When in this position the members may be moved through said spaces and the top member 50 swung independently of the back portion 6 to any desired position.

When the top member 11 is in closed position, the beveled edge 12 wedges the top firmly against the beads 2. At the same time the beveled edge effectually locks the 55 top against pivotal movement independent of the normal movement with the back portion 6. Thus any effort to swing the top upwardly without a corresponding rearward movement of the back portion 6 will cause 60 said edge to bear directly against the front member 3 and thereby effectually prevent the front edge from being swung upwardly even to a very slight degree such as might admit an instrument for prying open the 65 case. Suitable locking means 22 are mount-

ed upon the back of the back portion 6 to lock said portion 6 and the top member 11 in closed position.

In vending goods, the customer is given direct access to the merchandise from the 70 case as above described, thereby permitting said customer to select the particular articles desired. The doors 8 and 9 give access to the case without moving the top member 11 to open position whereby the attendant may 75 have convenient access to the case from the rear thereof.

The improved construction above described is extremely simple and efficient. The cams 13 and the beads 2 are simply constructed and easily applied upon the inside 80 of the end members 1 of the case. There are no light or delicate actuating mechanism whatever and no moving parts capable of becoming out of adjustment. The device 85 may thus be made extremely rugged and as the top member is effectually guided and held in correct position at all times the case is made substantially fool-proof, and suited to withstand all ordinary usage and abuse 90 by attendants and customers.

Having thus described my invention what I claim as new and desire to secure by Letters Patent is,

1. A new article of manufacture comprising a show-case provided with end portions having their upper edges inclined downwardly toward the front of the show-case; supporting beads arranged inside of each end portion parallel to and in spaced relation to said upper edges; a back portion pivotally mounted at its lower edge to said show-case; a top member pivotally connected to the top edge of the back portion and arranged to extend between the end portions and to rest upon the supporting beads; and means on the end portions for guiding the top portion upwardly and rearwardly to give access to the case when the back portion is swung rearwardly upon its pivot mounting.

2. A new article of manufacture comprising a show-case provided with end portions having their upper edges inclined downwardly toward the front of the show-case; supporting beads arranged inside of each end portion parallel to and in spaced relation to said upper edges; a back portion pivotally mounted at its lower edge to said show-case; a top member pivotally connected to the top edge of the back portion and arranged to extend between the end portions and to rest upon the supporting beads; and means for guiding the top portion upwardly and rearwardly to give access to the case when the back portion is swung rearwardly upon its pivot mounting; and means for normally preventing a pivotal movement of the top member when the top and back portions are in closed position.

3. A new article of manufacture comprising a show-case provided with end portions having their upper edges inclined downwardly toward the front of the show-case; supporting beads arranged inside of the end portions parallel to and in spaced relation to said upper edges; said beads forming acute angles with the front of the case; a back portion pivotally mounted at its lower edge to said show case; a top member pivotally connected to the top edge of the back portion and arranged to extend between the end portions and to rest upon the supporting beads, the forward edge of the top member being beveled to fit into the acute angle between the beads and the front of the case to wedge said top member against the beads and thereby form a dust proof joint and to lock the top member against pivotal movement when said top and back portions are in closed position; and means on the end portions for guiding the top member upwardly and rearwardly to give access to the case when the back portion is swung rearwardly upon its pivot mounting. 4. A new article of manufacture comprising a show-case provided with end portions having their upper edges inclined downwardly toward the front of the show-case; supporting beads arranged inside of the end portions parallel to and in spaced relation to said upper edges; a back portion pivotally mounted at its lower edge to said show case; a top member pivotally connected to the top edge of the back portion and arranged to extend between the end portions and to rest upon the supporting beads; and cams mounted upon the inner sides of the end portions adjacent the upper ends of the beads, said cams being arranged to be slidably engaged by the top member to guide same upwardly and rearwardly to give access to the case when the back portion is swung rearwardly upon its pivot mounting. 5. A new article of manufacture comprising a show-case provided with end portions having their upper edges inclined downwardly toward the front of the show-case; supporting beads arranged inside of the end portions parallel to and in spaced relation to said upper edges; a back portion pivotally mounted at its lower edge to said show case; a top member pivotally connected to the top edge of the back portion and arranged to extend between the end portions and to rest upon the supporting beads; and cams mounted upon the inner sides of the end portions adjacent the upper ends of the beads, said cams being arranged to be slidably engaged by the top member to guide same upwardly and rearwardly to give access to the case when the back portion is swung rearwardly upon its pivot mounting; and means mounted upon the top portion and arranged to engage the beads and the cams to normally prevent pivotal movement of the top independently of the movement by and with the back portion. 6. A new article of manufacture comprising a show-case provided with end portions having their upper edges inclined downwardly toward the front of the show-case; supporting beads arranged inside of the end portions parallel to and in spaced relation to said upper edges; a back portion pivotally mounted at its lower edge to said show case; a top member pivotally connected to the top edge of the back portion and arranged to extend between the end portions and to rest upon the supporting beads; and cams mounted upon the inner sides of the end portions adjacent the upper ends of the beads, said cams being arranged to be slidably engaged by the top member to guide the same upwardly and rearwardly to give access to the case when the back portion is swung rearwardly upon its pivot mounting; and means mounted upon the top portion and arranged to engage the beads and the cams to normally prevent pivotal movement of the top independently of the movement by and with the back portion; and means for locking the back portion and top members in closed position. 7. A new article of manufacture comprising a show-case provided with end portions having their upper edges inclined downwardly toward the front of the show case; a back portion pivotally mounted at its lower edge upon the show case; a top member pivotally connected to the upper edge of the back portion and arranged to extend between the end portions; beads mounted upon the inner sides of the end portions to form supports for the top member; cams mounted upon the inner sides of the end portions adjacent the upper ends of the beads, said cams being provided with inwardly extending flanges, arranged to be slidably engaged by the top member to guide said member upwardly and rearwardly to give access to the case when the back portion is swung rearwardly upon its pivot mounting; and means mounted upon the top member and arranged to engage the beads and flanges to normally prevent pivotal movement of the top independently of the movement by and with the back portion, and to limit the rearward movement of the top. 8. A new article of manufacture comprising a show-case provided with end portions having their upper edges inclined downwardly toward the front of the show-case; a back portion pivotally mounted at its lower edge upon the show-case; a top member pivotally connected to the upper edge of the back portion and arranged to extend between the end portions; beads mounted upon the inner sides of the end portions to form

supports for the top member; cams mounted upon the inner sides of the end portions adjacent the upper ends of the beads, said cams being provided with inwardly extending flanges longitudinally spaced from the adjacent ends of the beads, said flanges being arranged to be slidably engaged by the top member to guide said member upwardly and rearwardly to give access to the case
10 when the back portion is swung rearwardly upon its pivot mounting; and members secured upon the under side of the top member and arranged to engage the beads and cams to normally prevent pivotal movement
15 of the top member independently of the movement by and with the back portion and to limit the rearward movement of said top and back portions, said members being movable outwardly through the space between
20 the beads and cams to permit the top member to be swung outwardly for cleaning.

9. A new article of manufacture comprising a show-case provided with end portions having their upper edges inclined
25 downwardly toward the front of the show-case; a back portion pivotally mounted at its lower edge upon the show-case; a top member pivotally connected to the upper edge of the back portion and arranged to extend between the end portions; beads mounted upon the inner sides of the end portions to form supports for the top member, said beads forming acute angles with the front of the case and arranged to receive a beveled edge formed upon the front edge of the top member to wedge said top member tightly against the beads and to lock said member against pivotal movement when in closed position; cams mounted upon
30 the inner sides of the end portions adjacent the upper ends of the beads, said cams being provided with inwardly disposed flanges longitudinally spaced from the adjacent ends of the beads and arranged to be slidably engaged by the top member to guide said member upwardly and rearwardly to give access to the case when the back member is moved rearwardly upon its pivot mounting; and members secured upon the under sides of the top member and engaging the beads and flanges to normally prevent
35 pivotal movement of the top member independently of the movement by and with the back portion and to limit the movement of said top member; and means for locking the back and top members in closed position.

11. A new article of manufacture comprising a show-case provided with end portions having their upper edges inclined downwardly toward the front of the show-case; a back portion pivotally mounted at its lower edge upon the show-case; a top member pivotally connected to the upper edge of the back portion and arranged to extend between the end portions; beads mounted upon the inner sides of the end portions to form supports for the top member, said beads forming acute angles with the front of the case and arranged to receive a beveled edge formed upon the front edge of the top member to wedge said top member tightly against the beads and to lock said member against pivotal movement when in closed position; cams mounted upon the inner sides of the end portions adjacent the upper ends of the beads, said cams being provided with inwardly disposed flanges longitudinally spaced from the adjacent ends of the beads and arranged to be slidably engaged by the top member to guide said member upwardly and rearwardly to give access to the case when the back member is moved rearwardly upon its pivot mounting; and members secured upon the under sides of the top member and engaging the beads and flanges to normally prevent
40 pivotal movement of the top member independently of the movement by and with the back portion and to limit the movement of said top member; and means for locking the back and top members in closed position.

10. A new article of manufacture comprising a show-case provided with end portions having their upper edges inclined downwardly toward the front of the show-case; a back portion pivotally mounted at its lower edge upon the show-case; a top member pivotally connected to the upper edge of the back portion and arranged to extend between the end portions; beads mounted upon the inner sides of the end portions to form supports for the top member, said beads forming acute angles with the front of the case and arranged to receive a beveled edge formed upon the front edge of the top member to wedge said top member tightly against the beads and to lock said member against pivotal movement when in closed position; cams mounted upon the inner sides of the end portions adjacent the upper ends of the beads, said cams being provided with inwardly disposed flanges longitudinally spaced from the adjacent ends of the beads and arranged to be slidably engaged by the top member to guide said member upwardly and rearwardly to give access to the case when the back member is moved rearwardly upon its pivot mounting; and members secured upon the under sides of the top member and engaging the beads and flanges to normally prevent
45 pivotal movement of the top member independently of the movement by and with the back portion and to limit the movement of said top member; and means for locking the back and top members in closed position.

11. A new article of manufacture comprising a show-case provided with end portions having their upper edges inclined downwardly toward the front of the show-case; a back portion pivotally mounted at its lower edge upon the show-case; a top member pivotally connected to the upper edge of the back portion and arranged to extend between the end portions; beads mounted upon the inner sides of the end portions adjacent the upper ends of the beads, said beads forming acute angles with the front of the case and arranged to receive a beveled edge formed upon the front edge of the top member to wedge said top member tightly against the beads and to lock said member against pivotal movement when in closed position; cams mounted upon the inner sides of the end portions adjacent the upper ends of the beads, said cams being provided with inwardly disposed flanges longitudinally spaced from the adjacent ends of the beads and arranged to be slidably engaged by the top member to guide said member upwardly and rearwardly to give access to the case when the back member is moved rearwardly upon its pivot mounting; and members secured upon the under sides of the top member and engaging the beads and flanges to normally prevent
50 pivotal movement of the top member independently of the movement by and with the back portion and to limit the movement of said top member; and means for locking the back and top members in closed position.

12. A new article of manufacture comprising a show-case provided with end portions having their upper edges inclined downwardly toward the front of the show-case; a back portion pivotally mounted at its lower edge upon the show-case; a top member pivotally connected to the upper edge of the back portion and arranged to extend between the end portions; beads mounted upon the inner sides of the end portions to form supports for the top member, said beads forming acute angles with the front of the case and arranged to receive a beveled edge formed upon the front edge of the top member to wedge said top member tightly against the beads and to lock said member against pivotal movement when in closed position; cams mounted upon the inner sides of the end portions adjacent the upper ends of the beads, said cams being provided with inwardly disposed flanges longitudinally spaced from the adjacent ends of the beads and arranged to be slidably engaged by the top member to guide said member upwardly and rearwardly to give access to the case when the back member is moved rearwardly upon its pivot mounting; and members secured upon the under sides of the top member and engaging the beads and flanges to normally prevent
55 pivotal movement of the top member independently of the movement by and with the back portion and to limit the movement of said top member; and means for locking the back and top members in closed position.

In witness whereof I hereunto set my signature.

JOHN E. MULLEN
